UNITED STATES PATENT OFFICE.

WILLIAM HARRY RUF, OF ROSELLE PARK, NEW JERSEY.

WIRELESS DETECTOR.

Application filed April 27, 1922. Serial No. 556,916.

To all whom it may concern:

Be it known that I, WILLIAM HARRY RUF, a citizen of the United States, residing in Roselle Park, in the county of Union and 5 State of New Jersey, have invented certain new and useful Improvements in Wireless Detectors, of which the following is a full, clear, and concise description.

My invention relates to wireless detectors, 10 my more particular purpose being to give the detector such form that during its active use it may be readily carried around upon the person without causing inconvenience to the individual carrying it, and also to confer upon the detector a high degree of sensitivity and to give the operator a special and immediate control over its sensitiveness, not generally attained in the use of a wireless detector.

Reference is made to the accompanying drawing forming a part of this specification, and in which like reference characters indicate like parts throughout the several figures.

Figure 1 is a side view showing a form of my device to be carried like a finger ring; the figure being mainly an elevation, one of the parts being shown partly in section.

Figure 2 is a side elevation of the mechanism appearing in Figure 1, and shows the addition of an inductance winding for adapting the detector for use with electromagnetic waves of great length.

Figure 3 is an edge view of the mechanism shown in Figure 2.

Figure 4 is a plan view of the detector shown in Figures 1 to 3 inclusive, and illustrates how the detector is mounted upon and carried by the operator's finger.

Figure 5 is a side elevation of another form of my invention adapted in this instance for use as a scarf pin.

A clip frame 6, made of metal and having the form of a yoke, is provided with slots 45 one of which is shown at 7, and is further provided with a pair of oppositely disposed portions 8, 8, each of arcuate form. These portions carry crown settings 9 and 10, the crown setting 9 being provided with upwardly extending fingers 11 integral with it, and the crown setting 10 being similarly provided with fingers 12.

Fitted neatly into the crown setting 9 and held firmly by the fingers 11 thereof is a 55 block 13, having a substantially cubical form and made of insulating material, such

as hard rubber or bakelite. The block 13 carries a metallic stem 14, having substantially the form of an inverted L, and provided with an eye 15, adapted for use as a 60 binding post. The stem 14 supports a whisker 16, having the form of a helical winding of wire provided with a point 17. The whisker stem 14 is by means of the block 13 insulated from the crown setting 9 65 and metallic parts immediately connected therewith.

The crown setting 10 carries a crystal of galena, silicon or the like, in the form of a block 18, upon which the point 17 rests 70 lightly.

The crown setting 10 carries a stem 19 extending upwardly from it and terminating in an eye 20, serving the purpose of a binding post.

An inductance winding 21 may be added, if desired, as indicated in Figure 2. This winding, when used, is located within the slots one which appears at 7, in Figure 1. The winding 21 is for the purpose of adding 80 inductance, in order to adapt the detector for use in connection with waves of great length. I do not show the electric connections for the winding 21, or for the other parts, as they constitute no part of my invention.

The detector as a whole is fitted upon the operator's finger 22, and is worn somewhat after the manner of a finger ring.

The operator by sliding the detector 90 lengthwise of the finger, or even by bending this finger, may cause the portions 8, 8, of the device to be forced slightly further apart or brought a little more closely together, so as to shift the position of the point 17 of the whisker 16, relatively to the adjacent face of the crystal 18.

The operator, by grasping the whisker stem 14 and turning the same slightly upon the block 13 as a center, can shift the whisker point 17 in the direction indicated by the broken line of arcuate form shown in Figure 4. Thus the operator is enabled to bring the whisker point into contact with any portion of the adjacent face of the crystal 18. Such being the case, it is an easy matter for the operator to make a very fine adjustment of the point 17 relatively to the crystal. In this connection I call attention to the fact that the operator, by very slight muscular movements due to sliding the detector upon his finger or by bending his finger as the case

may be, can shift the point 17 very slightly upon the adjacent face of the crystal; and then, by testing the wave reception in the conventional way and manipulating his finger accordingly, he can cause the detector to "follow up" any movement of the finger which, in practice, is found to give the best results. If, for instance, the operator finds that by bending his finger beyond a certain limit the efficiency of the reception is impaired, but by bending his finger up to the limit just mentioned the efficiency of the reception is improved, he bends his finger just far enough to get the best effect; and then if, after another moment, he finds that straightening the finger out improves the effect, he straightens his finger gradually until the detector works at its best. If the detector works very badly owing to the point 17 being in engagement with a portion of the crystal not sufficiently sensitive, the operator can bend or straighten his finger abruptly, or slide the detector along the finger, thus displacing the point 17 slightly upon the surface of the crystal. Again, the operator can grasp the whisker stem 14, and by turning it slightly as indicated in Figure 4, shift it so that the point 17 is brought into a more favorable position relatively to the crystal.

By practice the eye 15 is connected with an antenna of any appropriate kind, and the eye 20 is connected with a ground, either natural or artificial. This antenna and ground are preferably portable; that is carried around by the operator, and may be of any desired form suitable for this purpose. A pair of head telephones are bridged across from the eye 15 to the eye 20. I do not show these connections as they form no part of my invention.

In the form of my device shown in Figure 5 the detector is mounted upon a pin, suitable for use as a necktie pin or as a scarf pin.

A pin body 22 carries a slide 23, fitting upon it detachably but rather tightly, and provided with an eye 24. The operator removes the slide 23, thrusts the pin through the necktie or scarf, and replaces the slide 23. The slide 23 has a tendency to prevent the pin from being removed surreptitiously by any other person. The eye 24 serves the purpose of a binding post, or at least as one of the terminals of the detector.

The pin 22 carries a crown setting 25 consisting of a metallic cylinder and provided with upwardly extending metallic fingers 26. These fingers encompass and hold a crystal 27.

The crown setting 25 carries a stem 28 made of insulating material, preferably glass, this stem carrying an enlarged portion 29 fashioned into a bulb or globe. Mounted upon the enlarged portion 29 is a metallic cage 30, carrying a stem 31 extending upwardly from it. This stem is provided with

an eye 32, serving as a terminal of the detector, or practically speaking, as a binding post. The stem 31 carries a whisker 33 having a helical form and provided with a point 34. The whisker is made of metal, preferably platinum.

The point 34 engages the crystal 27, and may be shifted slightly in relation to the surface of the latter.

The eye 24 is connected with a suitable ground and the eye 32 is similarly connected with an appropriate antenna, the antenna and ground being preferably carried around by the operator who wears the pin.

My device is specially adapted for use in relations where the operator may wish to carry his receiving apparatus with him, and in some relations is useful for enabling an operator to remain as far as practicable unobserved while receiving wireless signals.

The apparatus is well adapted for certain kinds of service in the army or navy or by a police department or a detective bureau. Its main mission, however, is for use as a novelty, and especially by amateurs interested in the reception of broadcasting signals.

The uses to which my invention may be applied are so numerous and varied that I do not attempt to enumerate all of them.

Having thus described my invention, what I claim as new and desire to secure by Letters Patent is as follows.

1. A wireless detector comprising a frame provided with means for fitting it upon the human finger after the manner of a finger ring, and detector mechanism carried by said frame for the reception of wireless signals.

2. A device of the character described comprising a frame made of spring metal and provided with a pair of oppositely disposed portions for pressing against opposite sides of some portion of a person's anatomy for the purpose of holding said frame in position, and wireless detector mechanism carried by said frame.

3. A device of the character described comprising a frame made of metal and provided with a pair of oppositely disposed clamping members for holding said frame upon some part of a person's anatomy, an inductance coil mounted upon said frame, and detector mechanism carried by said frame.

4. A device of the character described comprising a frame provided with a pair of oppositely disposed spring members for clamping said frame upon some portion of a person's anatomy, a crown setting carried by one of said portions of said frame, a crystal fitted into said crown setting and supported thereby, and a metallic point supported by said frame and insulated therefrom for the purpose of engaging said crys-

tal and therewith forming a wave detector.

5. A device of the character described comprising a pair of oppositely disposed spring members formed to engage opposite sides of a part of a person's anatomy, so that muscular movements of said part may vary the distance apart of said spring members, and a crystal detector mounted partly upon one of said spring members and partly 10 upon the other of said spring members, so that said crystal detector may be adjusted by thus varying the distance apart of said spring members.

6. A device of the character described 15 comprising a pair of clamping members for engaging some part of a person's anatomy, said clamping members being movable relatively toward each other by muscular action of the anatomical part, a crown setting mounted upon one of said clamping members, a detector carried by said crown setting, another crown setting carried by the other of said clamping members, a member of insulating material held by said last 20 mentioned crown setting, a whisker stem supported by said member of insulating material, and a whisker carried by said whisker stem and provided with a point detachably engaging said detector crystal.

25 7. A device of the character described comprising a frame provided with a pair of oppositely disposed clamping members, a crown setting carried by one of said clamping members, a crystal fitted into said crown setting and supported thereby, a supporting member carried by said frame and insulated therefrom, said supporting member being provided with a portion extending adjacent said crystal and movable relatively 30 to said crystal, and a whisker carried by said supporting member and adjustably engaging said crystal.

35 8. A device of the character described comprising a frame, a crystal supported thereby, an insulating member supported by 40 said frame, a metallic member connected

with said insulating member and provided with a portion extending adjacent said crystal, said metallic member being mounted to turn slightly in relation to said insulating member, and a whisker carried by 50 said metallic member and movable therewith relatively to said crystal.

55 9. A device of the character described comprising a crown setting, means for mounting the same upon the person of a wearer, a crystal held by said crown setting, a whisker stem, and a whisker mounted upon said whisker stem and adjustably engaging said crystal.

60 10. A device of the character described comprising a frame to be fitted upon some part of a person's anatomy, said frame having two members movable relatively to each other, a crystal mounted upon one of said members, and a whisker supported by the other of said members and insulated therefrom, said whisker engaging said crystal.

65 11. As an article of manufacture, a frame made of sheet metal and provided with a 70 pair of oppositely disposed portions of arcuate form for the purpose of engaging opposite sides of the wearer's finger, and a pair of crown settings each carried by one of said oppositely disposed portions, for the 75 purpose of supporting a crystal detector.

80 12. A device of the character described comprising a frame having a pair of oppositely disposed clamping members for engaging opposite sides of the wearer's finger, a crown setting carried by one of said clamping members and provided with a plurality of metallic fingers, a crystal of substantially cubical form carried by said crown setting and clasped by said metallic 85 fingers, and a whisker supported by the other of said clamping members and insulated therefrom, said whisker being provided with a point for adjustably engaging said crystal.

WILLIAM HARRY RUF.
